[57] **CLAIM**

The ornamental design for a combined electrically heated windshield wiper and coiled electrical cord, as shown and described.

DESCRIPTION

FIG. 1 is a front elevation of a combined electrically heated windshield wiper and coiled electrical cord, the broken line drawing of a windshield wiper frame is for illustrative purposes only and forms no part of the claimed design;

FIG. 2 is a rear elevational view thereof, the broken line drawing of a windshield wiper frame is for illustrative purposes only and forms no part of the claimed design;

FIG. 3 is a fragmentary, top, front perspective view thereof, on an enlarged scale, the heated wiper blade is partially shown for clarity of illustration;

FIG. 4 is a left end view thereof, on an enlarged scale;

FIG. 5 is a fragmentary, top, rear perspective view thereof, on an enlarged scale, the heated wiper blade is partially shown for clarity illustration;

FIG. 6 is a right end view thereof, on an enlarged scale;

FIG. 7 is a top plan view thereof;

FIG. 8 is a bottom plan view thereof.
